UNITED STATES PATENT OFFICE.

ALBE C. HEATH, OF MANCHESTER, NEW HAMPSHIRE.

MACHINE FOR BRUSHING AND CLEANING CLOTH.

SPECIFICATION forming part of Letters Patent No. 439,949, dated November 4, 1890.

Application filed March 14, 1888. Serial No. 267,147. (No model.)

To all whom it may concern:

Be it known that I, ALBE C. HEATH, a citizen of the United States, residing at Manchester, in the county of Hillsborough and State 5 of New Hampshire, have invented certain new and useful Improvements in Machines for Brushing and Cleaning Cloth; and I do hereby declare the following to be a full, clear, and exact description of the invention, such as 10 will enable others skilled in the art to which it appertains to make and use the same.

This invention relates to machines for brushing and cleaning cloth, especially cotton cloth, the object being to effectually remove all dust and lint from the surface of the 15 finished fabric before it is folded for the market; and the invention consists in the construction, arrangement, and combination of parts, substantially as will be hereinafter described and claimed.

In the accompanying drawings, Figure 1 is a side elevation of my improved machine for brushing and cleaning cloth. Fig. 2 is a vertical cross-section on the line $x x$ of Fig. 1.

Similar letters of reference designate corresponding parts in both figures.

With the machinery employed for the purpose in cotton-mills the cloth has heretofore commonly been finished by the use of brush-30 rollers situated in a horizontal position, so that the cloth while undergoing the operation of being brushed runs horizontally through the rollers. By this method, however, the cloth is only imperfectly cleaned or brushed, 35 for a large portion of the dust remains upon and is carried along with the cloth after it has left the brushes. My invention aims to obviate these disadvantages by employing a novel construction and arrangement of parts 40 by means of which the cloth may be effectually cleaned.

In my machine, instead of having the cloth travel horizontally through the rollers, I cause it to move vertically through the machine 45 from the bottom to the top, the brush-rollers being located on opposite sides of it, and suitable guides, &c., being employed to keep it moving in the right direction. Moreover, each brush or cleaning device will be provided 50 with its own individual and separated dust "outlet," "chute," or "throat," as it may be indifferently termed, whereby the dust and lint may

be conveyed into the receptacle placed to receive it. With this provision of separate dust-chutes the possibility of the dust which is 55 brushed or scraped off the cloth by one roller being commingled with the dust taken from another roller is entirely prevented.

Such being a general indication of the leading principles of my invention, I proceed to 60 describe in detail the construction of the machine.

A denotes a web of cloth, which passes vertically upward through the machine, at the top of which it passes over guide-rollers $f f$, 65 whereby it is directed out of the machine. The cloth is kept in its vertical position and guided in its movements by means of horizontal bars or rollers $c c c$, which are secured in the frame-work B of the machine. The 70 bars or rollers $c c c$ are arranged above each other in such a manner that the alternate ones will lie in the same vertical plane. This enables the fabric or cloth which is guided to maintain almost a straight vertical position, 75 because each alternate bar or roller is located on the opposite side of it from its successor and predecessor, as will be seen upon inspection of the sectional view of Fig. 2.

The frame-work B of my improved machine 80 may vary considerably in structure without departing from my invention, it being only essential that some suitable frame-work be provided wherein the guide-bars, the brush-rollers, the guide-rollers, the dust-chutes, and 85 the other parts of the detailed structure of the mechanism which I employ for carrying my invention into practical effect may be suitably located. I will not therefore enter into any specific description of the construction of the frame-work, but merely state that 90 it is properly made to support the several parts of the invention.

On opposite sides of the cloth are located brush-rollers b . They are suitably constructed 95 to brush the cloth. The upper two are preferably bristle brushes. They are carried by shafts C, which are journaled in the frame of the machine and provided with pulleys g for the application of the driving-belts. In the 100 example of machine illustrated in the drawings I employ six brush-rollers, three being located on each side of the cloth. They are situated in such a manner as to come in con-

tact with the cloth at points between the 5 guide-bars *c c*. Said bars guide the cloth and make a tension thereon so as to prevent it from vibrating while the brush-rollers are acting upon it to remove the dust and lint. Said rollers *b* may be emery-rollers, or they may be constructed in any manner to facilitate the accomplishment of their purpose.

It becomes necessary to provide chutes or 10 outlets whereby the dust, lint, and other refuse which is collected from the cloth by means of the brush-rollers may be conveyed away.

15 *E E* represent dust-boxes, which are placed in the bottom of the machine, and are adapted to receive the dust, &c., which is thrown into them by the chutes. In order to construct these chutes, plates or partitions *d d' d² d³*, &c., are provided. The sectional view clearly 20 indicates their arrangement. They lie in an inclined position in the frame-work. The partition *d* is located to partially surround the lower of the brush-rollers, and its upper edge lies in close proximity to the third guide-bar 25 from the bottom, there being only enough space left between said guide-bar and the edge of the partition *d* to permit the passage through it of the web of cloth *A*. The partition *d* forms in connection with the partition *d⁴* of the dust-box (said partition *d⁴* reaching to a point in close proximity to the lower guide-bar) a chute or throat which will receive all of 30 the dust collected by the lower brush-roller and conduct the same into the dust-box *E*. The partition *d'*, which extends upward so that its 35 upper edge is in close proximity to the fourth guide-bar from the bottom, and which partially surrounds the second brush-roller, forms in connection with the partition *d⁵*, that extends to near the second guide-bar, a throat or 40 chute for receiving the dust collected by the second brush-roller and carrying it down into the dust-box. Furthermore, the partition *d²*, the upper edge of which is close to the fifth 45 guide-bar from the bottom, partially surrounds the third brush-roller, and in connection with the partition *d* forms an outlet for carrying dust into the box *E*. The upper side of the partition *d²* serves as an inclined wall to 50 conduct the dust collected by the brush immediately above it down to the dust-box. The partition *d³* is so located that its upper edge

will come close to the upper guide-bar, and it 55 partially surrounds the fourth brush-roller from the bottom, and forms with the partition *d'* a throat for the dust collected by the fourth brush-roller, while the upper surface of said portion *d³* constitutes a plane for directing the dust from the upper brush toward the dust-box. 60

Although I have described in detail the location of the several partitions which constitute the throats or chutes for the different brush-rollers, I do not intend to confine myself to this arrangement, but reserve the liberty 65 of varying the same within wide limits for accomplishing the same result.

The operation of my improved machine will be obvious from the foregoing description of the construction and arrangement of the several parts without need of further detail, for it will be obvious that as the cloth travels upward through the machine it will come in contact successively with each of the brush-rollers, which will act independently upon it, 70 collecting from it all the dust and lint which may be thereon and conveying the same into a dust-box. When the cloth at length emerges from the machine after having been subjected to several brushings, it will be found to be effectively cleaned of all dust and lint and in proper condition for folding for market. 75

Having thus described my invention, what I claim as new, and desire to secure by Letters Patent, is—

1. The combination of the guide-bars *c c*, the brush-rollers *b b*, and the partitions *d d' d² d³*, all arranged to clean a vertically-moving web of cloth, substantially as described. 85
2. The combination of the guide-bars arranged alternately on opposite sides of the cloth, as stated, the brush-rollers similarly arranged on opposite sides of the cloth in proximity to the guide-bars, the partitions which form the dust-chutes for the brush-rollers, the dust-boxes *E E*, and the guide-rollers *f f*, substantially as described. 90
3. The combination of the guide-bars arranged alternately on opposite sides of the cloth, as stated, the brush-rollers similarly arranged on opposite sides of the cloth in proximity to the guide-bars, the partitions which form the dust-chutes for the brush-rollers, the dust-boxes *E E*, and the guide-rollers *f f*, substantially as described. 95

In testimony whereof I affix my signature in presence of two witnesses.

ALBE C. HEATH.
